UNITED STATES PATENT OFFICE.

JAMES WOODS LLOYD, OF VANCOUVER, BRITISH COLUMBIA, CANADA.

DUCK DECOY.

Application filed November 23, 1921. Serial No. 517,338.

To all whom it may concern:

Be it known that I, JAMES WOODS LLOYD, a subject of the King of Great Britain, and a resident of the city of Vancouver, in the 5 Province of British Columbia, Canada, have invented certain new and useful Improvements in Duck Decoys, of which the following is a specification.

My invention relates to improvements in 10 duck decoys, with particular reference to those used in duck and other wild fowl shooting, and the object of my invention is to provide a device of this nature the construction of which is such that a number of 15 them can be parcelled together compactly and conveniently carried from place to place personally by the user, which device is strong while of light construction and weight, is simple and effective, and capable 20 of being manufactured and sold at a low cost.

I attain this object by the construction illustrated in the accompanying drawings in which—

25 Fig. 1 is a plan view of the decoy, folded for transportation.

Fig. 2 is a plan view of the decoy unfolded.

Fig. 3 is a side view, unfolded.

30 Fig. 4 is a sectional view along the line 4—4 of Fig. 2.

Similar parts are indicated by similar figures of reference throughout the several views.

35 1 indicates the base of the decoy formed out of a piece of board or other buoyant material, the length and breadth of which are such that it will not readily capsize under the pressure of the wind on the decoy 40 proper, when the same is erected and in use. The decoy proper, indicated by the numeral 2, consists of a piece of thin sheet metal or other suitable material formed to represent, when viewed from the side, the profile of a 45 duck, the lower edge of this metal portion being turned at right angles to the main portion, as at 3, and in the lower edge of the main portion 2 and extending into the turned over portion 3 are provided apertures 50 4 and 5, these apertures being spaced apart and towards the head and tail end of the profile member 2 respectively.

Through the apertures 4 and 5 extend transversely of the base wires 6 and 7, the inner ends 8 and 9 of which are turned 55 downwardly and secured into the board in

any suitable manner and preferably at a point slightly beyond the longitudinal axis of the board, while their outer ends are bent at right angles to the main portion, as at 10. 60 and 11, the extremities of the right angled ends being then secured into the edge of the base 1, as shown. The space 12 between the wires and the base at their inner ends is such that the right angularly turned portion 3 65 of the profile member will fit therebetween to hold the profile erect without rocking when in the effective position shown in Fig. 4, while the space 13 between the outer ends of the wires and the base is slightly greater 70 than the width of the portion 3, from which it will be seen that when the decoy proper is erected in the effective position substantially centrally of the base the portion 3 is held between the inner ends of the wires 75 and the base so that it may be slid outwardly along the wires to the outer ends of the same and then folded down to lie on the base 1, as shown in Fig. 1.

14 indicates a hole formed in the base 80 at a suitable point within which is swingably mounted a ballast weight 15, capable of being swung up to lie entirely within the hole 14 or down to depend vertically from the base, this weight being narrower at its 85 midlength than at its outer end so that a convenient portion 16 is provided around which the anchor cord 17 may be wound when not in use, one end of the cord being attached to a hole 18 in the weight 15 while 90 at its opposite end is secured the anchor weight 19, the width of which is not greater than that of the ballast weight 15 so that it may lie thereon without projecting over it at its edges. Thus, when the decoy is not 95 in use the anchor cord may be wound around the portion 16 and the anchor weight 19 laid on the face of the wide end of the ballast weight 15, which may be then swung up into the hole 14 so that the hole then contains 100 both the weights and the cord and therefore when the decoy is out of use and ready for packing nothing will project on the under-side of the base 1. In use, of course, the weight 15 is swung down, the cord 17 unwound, and the anchor weight 19 dropped to the bottom to anchor the decoy in position.

From the foregoing it will be seen that I have devised a simple, strong, and effective 110 decoy for wild fowl shooting, the construction of which is such that a number of them

may be formed into a light compact parcel for convenient transportation.

What I claim as my invention is:—

1. A device of the class described comprising, a base provided with an opening intermediate its length and breadth, a decoy member, wires secured to said base passed through the decoy to foldably connect it to the base, a ballast weight secured at one end 10 to one side of the base opening capable of being swung to lie wholly within the opening or to depend vertically therefrom, its free end being broadened, an anchor cord one end of which is attached to said ballast 15 weight, and an anchor weight secured to the opposite end of the cord the width of which is not greater than that of the broadened end of the ballast weight whereby both weights and the anchor cord when wound 20 around the ballast weight may all lie within the base opening when swung thereinto.
2. A device of the class described comprising, a ballasted base, a decoy member formed as a profile out of a thin metal sheet the lower edge of which is turned at right 25 angles and provided with spaced apertures towards the head and tail ends, wires passed freely through said apertures and secured at their opposite ends into the base and 30 transversely of the same, the inner ends of said wires being spaced close to the base a short distance beyond the longitudinal axis of the same and their outer ends being spaced above the base a distance slightly 35 greater than the width of the right angled portion of the decoy member.

3. A decoy comprising a base member, a profile member and rods passing loosely through the profile member and anchored to the base member, said rods serving to hold 40 the profile member to the base member in slideable and foldable relation therewith.

4. A decoy comprising a base member, a profile member and rods having their intermediate portions passing loosely through the 45 profile member in spaced relation to the base member and having the end portions thereof anchored to said base member, said rods serving to hold the members together in slideable and foldable relation.

5. A device according to claim 4, in which the rods are inclined with respect to the base member.

6. A decoy comprising a base member, a profile member held to the base member in laterally slideable and foldable relation therewith, the connection between the members being such as to permit the profile member to assume an erect position when at the center of the base and to be folded against the 55 base when shifted toward one side thereof.

7. A decoy member having a base provided with an opening, a ballast element pivoted to the base and an anchor weight suspended from the ballast element adapted at 60 65 times, to be superimposed upon the ballast element and moved therewith to an inoperative or out-of-the-way position within said opening.

Dated at Vancouver, B. C., this 12th day 70 of November, 1921.

JAMES WOODS LLOYD.
